UNITED STATES PATENT OFFICE

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA

PROCESS OF CRACKING HYDROCARBON OILS

Application filed December 12, 1918. Serial No. 266,396.

This invention relates to a process of cracking hydrocarbon oils and has among its salient objects, to provide an improved process in which the vapors which pass off from the vapor chambers are subjected to the action of a reflux condenser and the condensed portions thereof returned to the system at a point remote from the vapor zone; to provide a process of the character above referred to in which the condensate from the reflux condensers is returned to or near a point where the oil to be treated enters the system and at a relatively cool part of the system; to provide a process of the character above referred to in which the oil is subjected to the pressure of the generated vapors during treatment; to provide a process adapted for continuous operation as distinct from batch operation; and in general to provide improvements of the character referred to.

In the drawings:

Fig. 1 and 1A together, form a side elevation of the apparatus with parts shown in section.

Figs. 2 and 2A together, form a plan view with parts shown in section and other parts broken away.

Referring to the drawings, 1 designates the furnace provided with bridge wall 2, flue 3 and stack 4. The furnace may be separated into two compartments by means of dividing wall 5. Within the furnace chambers are mounted two sets of tubes 6 and 7 mounted on suitable supports 8. The tubes 6 are relatively smaller than the tubes 7. The tubes 6 may be from an inch in diameter to six inches and the tubes 7 from 8 inches to 20 inches in diameter although it is to be understood that I do not limit myself to a tube of any particular size nor to the number or length of the tubes. These must vary as conditions require and will be apparent to one skilled in the art. The ends of the tubes are provided with cap members 9 which can be removed to permit the ends of the tubes being opened and the tubes cleaned. Instead of removing the caps 9 they may be provided with suitable doors or closure members (not shown). The oil to be treated is fed by means of a pump (not shown) from any source of supply through

the feed pipe 10 to one end of the coil 6 as shown at 11. The pipe 10 may be provided with a controlling valve 12. The oil passes through the coil 6 to connecting pipe 13 to one end of the large coil 7 as shown at 14. The vapors can pass out of the coil 7 through upright pipe 15 which is connected at its lower end to manifold 16 leading from adjacent ends of the large tubes of the coils 7. At its upper end, the pipe 15 is connected to a horizontal cross pipe 17 from either end of which lead downwardly extending vapor lines 18 and 19. In a generally similar manner, the other end of the large coil 7 is connected to riser 20, the upper end of which is connected to horizontal branch pipe 21 which is provided with a pair of downwardly extending vapor lines 22 and 23. The downwardly inclined vapor lines 18, 22, 23 and 19 are connected to tank 24. This tank 24 connects with an aerial condenser 25 provided with a series of upright pipes 26. The upper end of the aerial condenser is connected by pipes 27 and 28 to a water condenser 29. The water condenser 29 is connected by the pipe 30 to a receiving tank 31. The condensed vapors are drawn off through pipe 32 controlled by throttle valve 33. The gas escape pipe 34 is also provided with throttle valve 35. The receiving tank is provided with pressure gauge 36, liquid level glass 37 and safety valve 38.

As a novel feature of the process and apparatus the vapors which are condensed in the lines 18, 22, 23 and 19 and in the aerial, 85 are collected in the tank 24. The condensed vapors from the tank 24, which tank serves in effect as a stabilizer, are drawn out from the end of the tank from pipe 39 to pipe 40. From pipe 40 the condensed vapors are delivered to pipe 41 to the small coil 6 as shown at 42. These condensed vapors can either pass by gravity to the coil or can be forced in by means of a pump 43. This pump is interposed in the line 40 by branches 44 and 45 controlled by valves 46 and 47. A valve 48 is interposed in the line 40. When the valves 46 and 47 are closed, the pump is not used in which case the valve 48 is open. If it is desired, to use the pump, the valve 48 is closed 100

and the valves 46 and 47 opened. The oil is drawn off from the larger coil through the draw off lines 52 and 53 controlled by the valve 54. Gas or fuel oil for the burners are fed through lines 49 to pipes 50 and 51 which supply the burners (not shown).

The process is operated as follows: the oil is fed into the small coil continuously at desired rate and is there subjected to heat. The oil as it passes through the smaller coil may be said in effect to pass through the heating or cracking zone. The oil then passes to the larger coil or vapor zone. The undistilled portion of the oil is drawn off through the draw off lines to a residuum tank. The vapors pass through the downwardly inclined vapor lines to the tank 24. The heavier vapors will condense either in the downwardly inclined lines in the tank or in the aerial and will be drawn from the tank by gravity or by means of the pump, back to the inlet side of the small coil. The advantage of this method of treating the heavy condensed vapors is that they are continuously being returned to the heating zone but inasmuch as they are not permitted to fall back into the vapor zone as is the usual process, they do not tend to unduly cool the vapors in the vapor zone. This method of handling the heavy condensed vapors not only greatly lowers the fuel cost but results in a better operation. By controlling the temperature of the tank 24 and the vapor lines, anything below the given boiling or end point can be prevented from passing to the water condenser. This can be controlled either by the number or area of the vapor lines or by applying a cooling member not shown to the tank 24. The oil is maintained under pressure during distillation and condensation by regulating the distillate and gas valves of the receiver tank. The pressure may be maintained from 50 to several hundred pounds and the temperature from 500° F. upwardly. The following illustrative run may be given: In cracking gas oil from the Kansas or Oklahoma fields, of from 32° to 34° Baumé, at the same time maintaining a pressure of 100 to 150 lbs. upon the system a yield of from 50% to 60% distillate may be obtained. By re-distillation about 50% distillate may be obtained therefrom, having a boiling point of approximately 400° F.

By the terms, mechanical, imposed, applied or forced pressure, as used in the claims in describing a return flow of reflux oil to the heating coil, or the return flow of a mixture of reflux oil and charging stock, it is meant that the reflux oil or the mixed reflux oil and charging stock in either instance is positively forced to the coil by being first compelled to be subjected to the action of a mechanical pressure applying element before admission to the heating coil, and these terms do not cover a process where a stream of reflux oil

flows from a reflux condenser under a head or gravity pressure to a stream of charging stock flowing under a mechanical pressure to the coil, and which reflux oil is assisted in its merger with the charging stock by being drawn into said rapidly flowing stream of charging stock by reason of suction or entrainment, or both, due to the velocity of said stream at the point the reflux oil merges therewith while under a gravity pressure.

I claim as my invention:

1. A process of converting heavy into lighter hydrocarbons, consisting in passing a stream of oil through an elongated heated passageway to be heated to a cracking temperature by passing therethrough, in delivering the heated oil to an enlarged zone where substantial vaporization occurs, in discharging vapors to a dephlegmator where the insufficiently cracked vapors are condensed, in introducing a charging stock to said elongated heated passageway consisting of reflux condensate from said dephlegmator and charging stock from a source of supply produced by advancing the reflux condensate and charging stock toward one another in separately moving streams each under a mechanical pressure, in merging said separately moving streams of oil while each is advancing under pressure to permit intermingling thereof and passage through said elongated passageway, in removing residue from said enlarged zone without permitting intermingling thereof with the oil in the heating zone, and in maintaining a superatmospheric pressure on the oil in said system.

2. A process for converting heavy into lighter hydrocarbons, consisting in passing in an advancing direction a stream of oil through a heating coil where said oil is heated to a cracking temperature, in delivering the heated oil to an enlarged zone where vaporization occurs, in passing vapors from said zone to a reflux condenser where the insufficiently cracked vapors are condensed, and in continuously charging said heating coil with reflux condensate from said reflux condenser and charging stock by feeding said reflux condensate and charging stock in separate continuously moving streams each under a mechanical pressure, in merging said independent streams while under pressure, and passing the mixed oils through said coil, in withdrawing residue from said enlarged zone without admitting the same to said heating coil, and in maintaining a superatmospheric pressure on the oil in said system.

3. A process for treating hydrocarbon oil, consisting in raising the oil to a cracking temperature while passing through a continuous elongated passageway disposed within a heating furnace, in delivering the heated oil to a second zone where vaporization occurs, in discharging vapors from said

- second zone to a reflux condenser where the insufficiently cracked vapors are condensed, in advancing the reflux condensate from said reflux condenser and raw charging stock from a source of supply in separate streams each under a pump pressure, in merging said separately moving streams of oil at the time each stream is advancing under pressure to cause intermingling thereof and subsequent passage through said elongated passageway, in withdrawing continuously residual oil from said vaporizing zone without again admitting said oil to said elongated passageway, and in maintaining a superatmospheric pressure on the oil undergoing treatment.
4. A process for converting heavy into lighter hydrocarbons, consisting in passing in an advancing direction a stream of oil through a heating coil where said oil is subjected to a cracking temperature, in delivering the heated oil to an enlarged zone where vaporization occurs, in passing vapors from said zone to a reflux condenser where the insufficiently cracked vapors are condensed, in discharging reflux condensate from the condenser into a receiver where a pool of said condensate accumulates above the level to the entrance of said cracking coil, in advancing reflux condensate from said pool and raw charging stock from a source of supply in separate streams each under a mechanical pressure, in merging said separately moving streams of oil at a time when each stream is advancing under a pressure for passage through said heating coil, in withdrawing residuum from said expansion zone without admitting any portion thereof to the heating coil, and in maintaining a superatmospheric pressure on said system.
5. A process for converting heavy into lighter hydrocarbons, consisting in passing a stream of oil through a heating coil to be subjected to a cracking temperature, in delivering the heated hydrocarbon oil to an enlarged zone where conversion occurs, in preventing a return of residual oil from said enlarged zone to said coil, in passing generated vapors to a reflux condenser where the insufficiently cracked vapors are condensed, in advancing reflux condensate from said condenser, and a stream of charging stock from a source of supply, in separately moving bodies each under a mechanical pressure, in introducing said separately moving bodies while each is advanced under a pressure to said heating coil for passage therethrough, and in maintaining a superatmospheric pressure on the oil undergoing conversion in said coil and said enlarged zone.
6. A process for converting heavy into lighter hydrocarbons, consisting in passing a stream of oil through a heating coil where said oil is subjected to a cracking temperature, in delivering the highly heated oil to an enlarged zone where conversion of the oil occurs, in passing vapors generated from the converted oil to a reflux condenser where the insufficiently cracked vapors are condensed, in advancing the reflux condensate from said condenser and charging stock from a source of supply in separately moving bodies each under an imposed mechanical pressure, in merging said separately moving bodies for passage in an intermingled condition through said heating coil, in substantially continuously withdrawing residuum from said enlarged zone without again admitting the same to the heating coil, and in maintaining a superatmospheric pressure on the oil in said coil and in said enlarged zone.
7. A process for converting heavy into lighter hydrocarbons, consisting in passing a stream of oil through a heating coil where said oil is subjected to a cracking temperature, in delivering the highly heated oil to an enlarged zone where conversion of the oil occurs, in passing vapors generated from the converted oil to a reflux condenser where the insufficiently cracked vapors are condensed, in advancing the reflux condensate from said condenser and charging stock from a source of supply in separately moving bodies each under an imposed mechanical pressure, in merging said separately moving bodies for passage in an intermingled condition through said heating coil, in substantially continuously withdrawing residuum from said enlarged zone without again admitting the same to the heating coil, and in maintaining a superatmospheric pressure on the oil in said coil and in said enlarged zone.
8. A process of converting heavy into lighter hydrocarbons consisting in passing oil under pump pressure through a coil in a heating zone, in delivering the heated oil to an enlarged chamber where vaporization occurs, in removing vapors and passing them through a reflux condenser, in collecting an accumulated body of reflux condensate maintained in advance of the entrance to an independent feeding pump, in continuously forcing condensate from said body by said independent pump to the advancing stream of charging stock passing to said heating coil, in removing residue after said vaporization from the system without permitting intermingling of any substantial portion thereof with the oil in the heating coil, and in maintaining a superatmospheric pressure on the oil undergoing treatment.
9. A process of converting heavy into lighter hydrocarbons, consisting in passing a stream of oil through an elongated passageway to be subjected to a cracking temperature, in delivering the heated oil to an enlarged zone where substantial vaporization occurs, in discharging vapors to a dephlegmator where the insufficiently cracked vapors

- are condensed, in collecting the condensate in an oil body, in introducing reflux condensate from said collected body and charging stock from a source of supply to the elongated passageway by advancing the reflux condensate and charging stock toward one another in separately moving streams each under a mechanical pressure, in merging said streams for passage in an intermingled condition through the elongated passageway, in removing residue from said enlarged zone without permitting intermingling thereof with the oil in said elongated heated passageway, and in maintaining a superatmospheric pressure on the oil in said system.
10. A continuous process for cracking hydrocarbons consisting in passing the same in an advancing direction in a stream through a heating coil to be subjected to a cracking temperature, in transferring the oil to a reaction zone where vaporization of a substantial portion thereof occurs, taking off the vapors and subjecting them to a reflux condensing action, in passing reflux condensate and charging stock in streams, each moving under separately applied mechanical pressure and uniting said streams for admission to the inlet side of said coil, in withdrawing residue from said reaction zone without permitting intermingling of any portion thereof with the oil entering the heating coil, and in maintaining a superatmospheric pressure in said system.
